UNITED STATES PATENT OFFICE.

PIETER DE LANGE AND ROBERT AERNOUT BARON VAN LYNDEN, OF Utrecht, NETHERLANDS, ASSIGNEES, BY MESNE ASSIGNMENTS, TO AMERICAN THERMOPHONE COMPANY, OF BOSTON, MASSACHUSETTS, A CORPORATION OF MASSACHUSETTS.

THERMIC TELEPHONE AND ITS MANUFACTURE.

1,321,989.

Specification of Letters Patent.

Patented Nov. 18, 1919.

Application filed November 4, 1915. Serial No. 59,619.

To all whom it may concern:

Be it known that we, PIETER DE LANGE and ROBERT AERNOUT BARON VAN LYNDEN, both subjects of the Queen of the Netherlands, and residing at Utrecht, in the Netherlands, have invented new and useful Improvements in Thermic Telephones and Their Manufacture, of which the following is a specification.

- 10 Our invention relates to the manufacture of supports for the heating conductors of thermic telephones. As is well known, the manufacture of heating conductors for thermic telephones offers difficulties when it is to be practised on a large scale. The object of our invention is to enable the building up of arc-shaped or looped conductors to be effected on a large scale in a simple and yet reliable manner.
- 15 According to this invention, the ends of the heating conductor wires which are bent at an angle, to the branches of the wire, are forced into grooves of a support, so that the heating conductors are connected to said support without special fixing means.

20 Two ways of supporting arc-shaped conductors according to this invention are illustrated by way of example in the accompanying drawing in which Figures 1 and 2 are perspective views illustrating two forms of supports and wires embodying our present invention, and Figs. 3 and 4 are perspective views of two forms of wire loops suitable for use in connection with our present invention.

25 In the construction shown in Fig. 1 a heating conductor wire consisting of several arcs or loops 1 and of straight intermediate portions 2, is connected to its support 3 made of insulating material, by pressing the straight intermediate portions 2 into a groove 4 in the support 3. The arched heating conductors thus produced will naturally be in series connection. The support 3, which in this case must be made of insulating material, may contain two or more grooves 4, for introducing several sets of heating conductors. It will be seen that the pressure exerted on the bent ends when pressing them into the grooves is in a direction away from the central portion of the

arc; in other words, such pressure will bring the center of the arc nearer to the support.

Fig. 2 shows a circular heating conductor support 5 provided with an annular groove 6 and a groove 7 extending along a diameter. The heating conductor wire which consists of several arcs 8 and straight or approximately straight intermediate portions 9, is secured to the support 5 in the manner shown in the drawing, by pressing the said intermediate portions 9 into the grooves 6 and 7. In this case also the heating conductors constituted by the loops 8, are in series connection.

The heating conductors connected to their support in the manner described, can be etched without difficulty to the desired sound-producer length, by dipping them to the proper depth in an etching bath with their central arc-shaped portions depending 70 downward.

The construction described could be of course carried out with single arc-shaped or looped heating conductor wires, such as are shown in Figs. 3 and 4. The branch 75 ends of the arc-shaped heating conductor wires which are bent at an angle to the branches may be of round cross section (Fig. 3) or flattened (Fig. 4). When the construction shown in Fig. 1, or that shown in Fig. 2, is made up of individual wires such as represented in Figs. 3 and 4, the adjacent ends of neighboring individual wires will be forced into a groove of the support in such a manner that such ends will be in 85 contact with each other, to properly conduct the current.

We claim:

1. The process of securing arc-shaped conductor wires of thermic telephones to their supports, which consists in bending the ends of said wires laterally and pressing said ends into grooves provided in the support, while leaving the arc portions of the wires projecting free from said support.

2. The process of securing arc-shaped conductor wires of thermic telephones to their supports, which consists in bending the ends of said wires laterally and pressing said ends, in a direction away from the central 100

portions of the arcs, into grooves provided in the support, while leaving such arc portions of the wires projecting free from said support.

5. 3. In a thermo-telephone, a heat unit comprising an insulating member having one or more grooves, and a series of wire loops in

electrical contact with each other and having their ends supported from displacement by the walls of said grooves.

In testimony whereof we have signed this specification.

PIETER DE LANGE.

ROBERT AERNOUT BARON VAN LYNDEN.
